UNITED STATES PATENT OFFICE.

HENRY JOSEPHSON, OF CLEVELAND, OHIO.

SHAFT-OPERATING MECHANISM.

1,234,344.

Specification of Letters Patent. Patented July 24, 1917.

Application filed March 22, 1917. Serial No. 156,714.

To all whom it may concern:

Be it known that I, HENRY JOSEPHSON, a citizen of the United States of America, residing at Cleveland, in the county of Cuyahoga and State of Ohio, have invented certain new and useful Improvements in Shaft-Operating Mechanism; and I hereby declare the following to be a full, clear, and exact description of the invention, such as will enable others skilled in the art to which it pertains to make and use the same.

This invention relates to improvements in mechanism for actuating rock-shafts, and pertains more especially to improved shaft-operating mechanism comprising a foot-lever operatively connected with an arm of a shaft for effecting the actuation of said arm in one direction against the action of a spring, a hand-lever arranged near the foot-lever and operatively connected with an arm of another shaft for effecting the actuation of said arm in one direction against the action of a spring and independently of the first-mentioned shaft, means normally locking said hand-lever against movement in the opposite direction, and means independent of said hand-lever for effecting the aforesaid actuation of the second-mentioned arm simultaneously with and during the aforesaid actuation of the first-mentioned arm by the foot-lever.

One object of this invention is to provide such a connection between the hand-lever and the arm of the second-mentioned shaft that during the actuation of said arm by the hereinbefore mentioned means employed in actuating said arm independently of the hand-lever, said hand-lever remains undisturbed and movement of said arm is therefore not accompanied by movement of the hand-lever.

Another object is to have the means employed, independently of the hand-lever, in actuating the arm of the second-mentioned shaft simultaneously with and during the actuation of the arm of the first-mentioned shaft by the foot-lever, not only simple in construction and readily applicable, but to have said means conveniently adjustable and readily accessible for repairs, renewal, cleaning and lubrication.

With these objects in view, and to the end of attaining any other object hereinafter appearing, this invention consists in certain features of construction, and combinations and relative arrangement of parts, herein-

after described in this specification, pointed out in the claims, and illustrated in the accompanying drawings.

In said drawings, Figures 1 and 2 are elevations of rock-shaft-operating mechanism embodying my invention and show two rock-shafts in cross-section. Fig. 3 is a horizontal section taken along the line 3-3, Fig. 1, looking upwardly. Fig. 4 is a horizontal section taken along the line 4-4, Fig. 1, looking downwardly. Fig. 5 is a horizontal section taken along the line 5-5, Fig. 1, looking downwardly. Fig. 6 is a vertical section taken along the line 6-6, Fig. 1. Portions are broken away in the drawings to reduce their size.

Referring to said drawings, A and a indicate portions of the stationary framework of a machine having shaft-operating mechanism embodying my invention. B indicates a suitably supported substantially horizontally arranged shaft having an upwardly projecting arm b which has its upper portion provided with a slot 10 extending to the upper extremity of the arm and through the arm at a right angle to the shaft. A pivotal bolt or member C extends laterally through and has bearing in the slotted or upper portion of the shaft-arm b and is parallel with the shaft B, and said pivotal member extends laterally through a rod E extending through said slot in a substantially horizontal plane. The rod E is therefore pivoted to the arm b of the shaft B substantially horizontally and parallelly with said shaft and employed in operatively connecting said arm with the lower end of an upright lever 12 which is fulcrumed at its upper end, as at 13, to the support a and is operatively connected centrally between its ends by a link 14 with a foot-lever G which is fulcrumed, as at 9, to said support. A spiral spring 15, connected at one end to said lever and at its opposite end to the support a, acts to retain said lever in its normal position, shown in Fig. 1.

By the construction hereinbefore described it will be observed that the rod E and the connected lever G are arranged at one side of the rock-shaft B. At the opposite side of and spaced from said shaft is a substantially horizontal rock-shaft H which is shown arranged somewhat lower than but substantially parallel with the shaft B. The shaft H has an upwardly projecting arm h having a slot 16 which extends to the upper

extremity of the arm and through the arm at a right angle to the shaft.

The rod E has a portion e thereof extending from the arm h of the shaft B in the direction of the arm h of the shaft H, and a sleeve K is arranged within the slot 16 of the last-mentioned arm and mounted on and adjustable endwise of the rod-extension e. Said sleeve is preferably provided in each side thereof with a screw-threaded hole 17 which extends laterally from the interior to the exterior of the sleeve and is adapted to be brought into registry with any cavity of a row of cavities 18 which are formed in and spaced longitudinally of the adjacent side of the rod-extension e by properly positioning the sleeve endwise relative to said rod-extension, and a set-screw f, which engages said hole in said sleeve and the cavity 18 which registers with said hole, is instrumental in securing said sleeve to the rod-extension e in the desired adjustment of the sleeve. The sleeve K is provided, at its outer end, with a downwardly projecting member 20 which is arranged and extends transversely of a substantially horizontally arranged circular bolt or member 21 which is substantially parallel with the shaft H and carried by the arm h of said shaft. Said bolt or member 21 of said arm h extends laterally and loosely through the slotted portion of said arm and is preferably located centrally between the upper and lower ends of the said arm and between the inner end of the sleeve K and the afore-said member 20 of said sleeve and contiguous to said member of the said sleeve. The downwardly projecting member 20 of the sleeve K is shown not only in contact with the member 21 of the shaft-arm h , but as extending circumferentially of said member of said arm and somewhat under the adjacent portion of said shaft-arm, as at 22, so as to prevent displacement of said member of said sleeve upwardly from said member of said shaft-arm. By the construction hereinbefore described it will be observed that the sleeve K, and consequently the member or portion 20 of said sleeve, are rigid and movable with the rod E during the movement of said rod by the actuation of the foot-lever G against the action of the spring 15, that the parts composing the operative connection between the shaft-arm h and the rod E are readily assembled, and conveniently accessible for cleaning, repairs and lubrication, that the rod E and said sleeve are relatively adjustable to effect an accurate adjustment of the member 20 of said sleeve relative to the member 21 of the shaft-arm h , and that said member of said shaft-arm cooperates with said member of said sleeve in forming means for preventing upward displacement of said sleeve.

The shaft-arm h is provided at its upper

end with a substantially horizontal pivotal member 24 which is parallel with the transverse member 21 of said arm and with the shaft H and extends through the upper end of the slot 16 in said arm. Loosely mounted on and embracing the pivotal member 24 is one end-portion of a rod L, and said end-portion of said rod extends through the upper portion of the slot 16 in the shaft-arm h . The rod L is operatively connected with the lower end of a hand-lever M preferably through the medium of a link which comprises an internally screw-threaded sleeve l screwed onto the correspondingly screw-threaded adjacent portion of the rod so as to render said link and said rod relatively adjustable, and said sleeve is provided at its outer end with two laterally spaced substantially parallel arms 25 which project endwise from said end of said sleeve and in the direction of the foot-lever G, and the hand-lever M extends between the outer ends of said arms and has a pin 26 extending laterally through said hand-lever and into slots 27 formed in and extending laterally through and longitudinally of the said arms. It will be observed therefore that the link comprising the sleeve l and its arms 25 projects outwardly from the rod L in the direction of the hand-lever M and is provided with one or more slots 27 arranged longitudinally of the link and having their outer end walls engaged by a member of said lever in the normal position of said rod. A nut 28 is shown mounted on the rod L at the inner end of the sleeve l. The hand-lever M is fulcrumed, as at m, to the support a in proximity to the foot-lever G, and a suitably applied spiral spring 30, which is connected at one end to the sleeve l and at its other end to the support a, acts to retain the rod L and the connected shaft-arm h in their normal position shown in Fig. 1, and in said position of said shaft-arm the transverse member 21 of said arm is in contact with the downwardly projecting member 20 of the sleeve K. The relative arrangement of the parts is such that in the normal position of the rod L and the connected shaft-arm h the slots 27 in the sleeve-arms 25 have their outer end walls, which face in the direction of said shaft-arm, engaged by the pin or projecting member 26 of the hand-lever M so that said rod and said shaft-arm h are free to move in the direction in which the other end walls of said slots face,—that is, in the direction of the foot-lever G,—independently of the hand-lever M and against the action of the spring 30.

As the arm h of the shaft H is free to be actuated in the direction of the levers G and M it will be observed that, during the actuation of the hand-lever M as required to move the connected rod L in said direction and

against the action of the spring 30, said arm *h* is actuated in said direction independently of the downwardly projecting member 20 of the sleeve K, and consequently the shaft H is actuated independently of the shaft B. When, however, the foot-lever G is actuated against the action of the spring 15 and in the direction required to effect the movement of the connected rod E toward the foot-lever, not only is the shaft B actuated but the shaft arm *h* is at once and positively actuated in said direction through the medium of the downwardly projecting member 20 of the sleeve K and the engaging transverse member 21 carried by said shaft-arm. It will be observed therefore that the arm *h* of the shaft H is provided, independently of the connection of the rod L to the shaft-arm *h*, with a transverse member such, for instance, as the pin or bolt 21 shown, and that said transverse member of said shaft-arm and the engaging downwardly projecting member 20 of the sleeve K have such relative arrangement that the arms *b* and *h* of the shafts B and H are simultaneously actuated in the same direction during the actuation of the foot-lever G in said direction, and that the arm *h* of the shaft H is free to be actuated in said direction so as to 30 actuate the shaft H independently of the shaft B.

The hand-lever M is shown arranged at one side of the support *a* which is provided in said side with a recess 31 in which is arranged a segmental rack R shown secured to said support. The rack R extends circumferentially of the under side and is arranged concentrically relative to the fulcrum *m* of the hand-lever M and has its teeth 40 formed at its under side, and a pawl *r* is normally in engagement with said rack and has an arm 32 which extends upwardly and is pivoted, as at 33, above the support *a* to the lever M, and has its axis parallel with the axis of the lever. Between the pawl-arm 32 and the lever M, above the axis of said arm, is arranged a spring 35 which is supported from the lever and acts to retain the pawl in its operative position. The relative arrangement of the parts is such that the rack R and pawl *r* do not interfere with the actuation of the hand-lever M against the action of the spring 30 as required to effect the actuation of the shaft-arm *h* in the direction of the foot-lever G independently of the shaft B, but locks said hand-lever against return movement upon said actuation of said shaft-arm by the hand-lever, as desired, and does not interfere with the movement 60 of said shaft-arm with the rod E during the movement of said rod by the actuation of the foot-lever against the action of the spring 15. It will be observed therefore that the hand-lever M is not disturbed during the actuation of the shaft-arm *h* with

the shaft-arm *b*, and that the actuation of the shaft-arm *h* with the shaft-arm *b* is not interfered with by the locking means comprising the rack R and pawl *r*.

What I claim is:

1. The combination, with a shaft having an arm, a rod operatively connected with said arm, and another shaft having an arm adapted to be rocked in one direction independently of the first-mentioned shaft, of a rigid projecting member connected to said rod and extending into proximity to the arm of the second-mentioned shaft, and a member carried by said arm of said second-mentioned shaft and arranged to be actuated by said projecting member during movement of said rod endwise in the required direction, said projecting member and the member to be actuated thereby being relatively adjustable.

2. The combination, with a shaft having an arm, a rod operatively connected with said arm, and another shaft having an arm adapted to be rocked in one direction independently of the first-mentioned shaft, a part adjustable endwise of said rod and provided with a projecting member extending into proximity to the arm of the second-mentioned shaft, and a member carried by the arm of said second-mentioned shaft and arranged to be actuated by said projecting member during movement of said rod endwise in the required direction, and means for securing said adjustable part to said rod in the desired adjustment of said adjustable part.

3. The combination, with a substantially horizontally arranged rock-shaft having an upwardly projecting arm, a member carried by said arm and substantially parallel with said shaft, and another shaft substantially parallel with the first-mentioned shaft and having an upwardly projecting arm, of an endwise shiftable rod operatively connected with the last-mentioned arm, and a rigid member connected to said rod and extending over the aforesaid member of the first-mentioned arm and having a downwardly projecting portion arranged to actuate said member of said first-mentioned arm during movement of said rod endwise in the required direction.

4. The combination, with a rock-shaft having an arm, a member carried by said arm and substantially parallel with said shaft, and another shaft having an arm, of an endwise shiftable rod operatively connected with the last-mentioned arm and having a portion which extends from said last-mentioned arm in the direction of the first-mentioned arm, a sleeve mounted on and adjustable endwise of said portion of said rod, and means for securing said sleeve to said portion of said rod in the desired adjustment of the sleeve, said sleeve having a member ar-

ranged to move the aforesaid member or the arm of the first-mentioned shaft during movement of said rod endwise in the required direction.

5 5. The combination, with a rock-shaft having an arm, another shaft having an arm, and a rod operatively connected with the last-mentioned arm and having a portion which extends from said last-mentioned arm
10 in the direction of the first-mentioned arm and is provided in each side thereof with a row of cavities spaced longitudinally of the rod, of a sleeve mounted on and adjustable endwise of said cavitated portion of said rod and provided with a screw-threaded hole which registers with one of said cavities and extends from the interior to the exterior of the sleeve, and a set-screw screwed into the sleeve at said hole and engaging the cavity
15 registering with said hole, said sleeve having a projecting member instrumental in effecting the actuation of the arm of the first-mentioned shaft during movement of the rod endwise in the required direction.
20 6. The combination, with a substantially horizontal rock-shaft having an upwardly projecting arm, a circular member which is substantially parallel with said shaft and carried by said arm, and another shaft ar-
25 ranged at one side of and substantially parallel with the first-mentioned shaft and having an upwardly projecting arm, of an end-
30 wise shiftable rod operatively connected with the last-mentioned arm and having a portion extending from said arm in the direc-
35 tion of and over the aforesaid member of the arm of the first-mentioned shaft, a rigid part mounted on and adjustable endwise of said portion of said rod, means for securing said
40 adjustable part to said rod in the desired adjustment of said adjustable part, and a rigid downwardly projecting member connected to said adjustable part and arranged to move the aforesaid member of the arm of the first-
45 mentioned shaft during movement of said rod endwise in the required direction and ex-
50 tends circumferentially of a portion of said member of said arm of said first-mentioned shaft.
55 7. The combination, with a rock-shaft having an arm provided with a slot extending laterally through said arm, a member carried by the slotted portion of said arm and arranged transversely of the slot, and
60 another shaft having an arm, of an endwise shiftable rod operatively connected with the last-mentioned arm and having a portion which extends into said slot and over said member of the arm of the first-mentioned
65 shaft, a sleeve mounted on and adjustable endwise of said rod, and means for securing the sleeve to the rod in the desired adjustment of the sleeve, the sleeve being provided at its outer end with a downwardly project-
70 ing member arranged to push the aforesaid

member of the arm of the first-mentioned shaft during movement of the rod endwise in the required direction.

8. The combination, with a rock-shaft having an upwardly projecting arm provided with a slot which extends laterally through the arm and having a member which is carried by the slotted portion of the arm and substantially parallel with said shaft, and another shaft arranged at one side of and substantially parallel with the first-mentioned shaft and having an upwardly projecting arm, of an endwise shiftable rod operatively connected with the last-mentioned arm and having a portion which extends from said last-mentioned arm into and through the aforesaid slot and over the aforesaid member of the first-mentioned arm, a sleeve mounted on and adjustable endwise of said rod, and means for securing the sleeve to the rod in the desired adjustment of the sleeve, the sleeve being provided at its outer end with a downwardly projecting member arranged to push the aforesaid member of the first-mentioned arm during movement of the rod endwise in the required direction. 70 75 80 85 90

9. The combination, with a rock-shaft having an arm, a lever operatively connected with said arm, another rock-shaft having an arm which is free to move in one direction independently of the first-mentioned arm, and means for effecting the movement of the second-mentioned arm in said direction simultaneously with and during the actuation of the first-mentioned arm in the required direction by the first-mentioned lever, of another lever employed in the actuation of the second-mentioned arm in the direction in which said arm moves during the aforesaid actuation of said second-mentioned arm simultaneously with and during the aforesaid actuation of the first-mentioned arm by the first-mentioned lever, and such an operative connection between the second-mentioned arm and the second-mentioned lever that said second-mentioned arm is free to move independently of said second-mentioned lever during the aforesaid actuation of said second-mentioned arm simultaneously with the first-mentioned arm. 110

10. The combination, with a rock-shaft having an arm, a foot-lever arranged at one side of said shaft and operatively connected with said arm, another rock-shaft arranged at the opposite side of the first-mentioned shaft and having an arm which is free to move in one direction independently of the first-mentioned arm, and means for effecting the movement of the second-mentioned arm in said direction simultaneously with and during the actuation of the first-mentioned arm in the required direction by the foot-lever, of a hand-lever arranged near the foot-lever and employed in the actuation of 130 120 125

the second-mentioned arm in the direction in which said arm moves during the aforesaid actuation of said second-mentioned arm simultaneously with and during the aforesaid actuation of the first-mentioned arm by the foot-lever, and such an operative connection between the second-mentioned arm and the hand-lever that said second-mentioned arm is free to move independently of the hand-lever during the aforesaid actuation of said second-mentioned arm simultaneously with the first-mentioned arm.

11. The combination, with a rock-shaft having an arm, a lever operatively connected with said arm, another rock-shaft having an arm which is free to move in one direction independently of the first-mentioned arm, and means for effecting the movement of the second-mentioned arm in said direction simultaneously with and during the actuation of the first-mentioned arm in the direction of the first-mentioned lever, of a rod operatively connected at one end to the second-mentioned arm, another lever employed in the actuation of said rod in the direction in which said rod moves during the aforesaid actuation of the second-mentioned arm simultaneously with and during the aforesaid actuation of the first-mentioned arm by the first-mentioned lever, and such an operative connection between said rod and the second-mentioned lever that the rod is free to move independently of said second-mentioned lever during the aforesaid actuation of said second-mentioned arm simultaneously with the first-mentioned arm.

12. The combination, with a rock-shaft having an arm, a foot-lever arranged at one side of said shaft and operatively connected with said arm, another rock-shaft arranged at the opposite side of the first-mentioned shaft and having an arm which is free to move in one direction independently of the first-mentioned arm, and means for effecting the movement of the second-mentioned arm in said direction simultaneously with and during the actuation of the first-mentioned arm in the direction of the foot-lever, of a hand-lever arranged near the foot-lever, a rod operatively connected at one end to the second-mentioned arm and extending from said arm in the direction of the hand-lever, and such an operative connection between the hand-lever and said rod that the rod is free to move independently of the hand-lever during the aforesaid actuation of the second-mentioned arm simultaneously with the first-mentioned arm.

13. The combination, with a rock-shaft having an arm, a lever operatively connected with said arm, another rock-shaft having an arm which is free to move in one direction independently of the first-mentioned arm, and means for effecting the movement of the second-mentioned arm in said direction

simultaneously with and during the actuation of the first-mentioned arm in the direction of the aforesaid lever, of a rod operatively connected at one end to the second-mentioned arm and extending from said arm in the direction of the aforesaid lever, a link carried by said rod and having a lateral slot arranged longitudinally of the link, and a lever having a member extending into the outer end-portion of said slot in the normal position of the rod.

14. The combination, with a rock-shaft having an arm, a lever operatively connected with said arm, another rock-shaft having an arm which is free to move in one direction independently of the first-mentioned arm, and means for effecting the movement of the second-mentioned arm in said direction simultaneously with and during the actuation of the first-mentioned arm in the required direction by the aforesaid lever, of a rod operatively connected with the second-mentioned arm and extending from said arm in the direction of the aforesaid lever, a link carried by said rod and having a slot arranged longitudinally of the link, and a lever having a member extending into the outer end-portion of said slot in the normal position of the said rod, the aforesaid link and said rod being relatively adjustable.

15. The combination, with a rock-shaft having an arm, a lever operatively connected with said arm, another rock-shaft having an arm which is free to move in one direction independently of the first-mentioned arm, and means for effecting the movement of the second-mentioned arm simultaneously with and during the actuation of the first-mentioned arm in said direction in the required direction by the aforesaid lever, a rod operatively connected at one end to the second-mentioned arm and extending from said arm in the direction of said lever, a link comprising a sleeve mounted on and secured to the other end of said rod, which sleeve has two laterally spaced substantially parallel arms projecting outwardly from the outer end of the sleeve, each arm of the sleeve having a slot extending laterally through and longitudinally of the arm, and a lever arranged between the arms of the sleeve and provided with a pin extending into the slots in said arms of the sleeve and engaging the outer end-portion of said slots in the normal position of the rod.

16. The combination, with a rock-shaft having an arm, a foot-lever operatively connected with said arm, another rock-shaft having an arm which is free to move in one direction independently of the first-mentioned arm, means for effecting the movement of the second-mentioned arm in said direction simultaneously with and during the actuation of the first-mentioned arm in

the required direction by the foot-lever, and means acting to retain said arms in their normal position, of a hand-lever arranged near the foot-lever and employed in the actuation of the second-mentioned arm in the direction in which said arm moves during the aforesaid actuation of said second-mentioned arm simultaneously with and during the aforesaid actuation of the first-mentioned 5 arm by the foot-lever, locking means for locking the hand-lever against movement in the opposite direction upon said actuation of said second-mentioned arm by the hand-lever, said locking means being normally operative, and such an operative connection between the second-mentioned arm and the hand-lever that said second-mentioned arm is free to move, independently of the hand-lever and connected locking means, during 10 the aforesaid actuation of said second-mentioned arm simultaneously with the first-mentioned arm.

17. The combination, with a rock-shaft having an arm, a lever operatively connected with said arm, another rock-shaft having an arm free to move in one direction independently of the first-mentioned arm, means for effecting the movement of the second-mentioned arm in said direction simultaneously with and during the actuation 25 30

of the first-mentioned arm in the required direction by the first-mentioned lever, and means acting to retain said arms in their normal position, of another lever employed in the actuation of the second-mentioned arm in the direction in which said arm moves during the aforesaid actuation of said second-mentioned arm simultaneously with and during the aforesaid actuation of the first-mentioned arm, locking means for locking the second-mentioned lever against movement in the opposite direction upon said actuation of said second-mentioned arm by said second-mentioned lever, said locking means being normally operative, and such an operative connection between the second-mentioned arm and said second-mentioned lever that said second-mentioned arm is free to move, independently of said second-mentioned lever and the connected locking means, during the aforesaid actuation of said second-mentioned arm simultaneously with the first-mentioned arm.

In testimony whereof, I sign the foregoing specification, in the presence of two witnesses.

HENRY JOSEPHSON.
